UNITED STATES PATENT OFFICE.

JOHN W. BARTH, OF PITTSBURG, PENNSYLVANIA.

AUTOMATIC CAR-COUPING.

No. 859,279.

Specification of Letters Patent.

Patented July 9, 1907.

Application filed September 28, 1906. Serial No. 336,602.

To all whom it may concern:

Be it known that I, JOHN W. BARTH, a resident of Pittsburgh, in the county of Allegheny and State of Pennsylvania, have invented a new and useful Improvement in Automatic Car-Couplers; and I do hereby declare the following to be a full, clear, and exact description thereof.

This invention relates to automatic car couplers and the object is to provide an automatic coupler of simple, cheap and strong construction and having only three main parts, namely: the coupler head, the knuckle and the locking pin, and the parts being so arranged that the locking pin when raised sufficiently to unlock the knuckle will automatically set so as not to again drop to locked position even though the cars do not immediately pull apart, and which upon being elevated to the full height will serve to throw the knuckle open.

A further object of the invention is to provide a coupler so constructed that it will lock when presented to the companion coupler at a decided angle, thus enabling couplings to be made on very sharp curves.

In the use of automatic car couplers it has long been recognized to be of advantage to throw the knuckle open by merely drawing up on the locking pin so as to avoid the necessity of the brakeman stepping in front of the car. Numerous arrangements have heretofore been provided for effecting this result but as far as I know such arrangements either necessitated the use of additional parts which added to the complication and weight of the coupler and generally are of weak construction, or else it necessitated a peculiar form of locking member, difficult of operation, expensive to make and withal weak. It is also desirable that after raising the locking pin it should set itself automatically so as not to again drop to locking position in order that if the cars do not immediately pull apart the brakeman need not retain hold of the unlocking lever but can at once pass on to some other place. Various schemes have also been used for accomplishing this result, many of which necessitated an extra part pivoted to the locking pin. It is also desirable that the couplers should automatically lock on sharp curves, such as occur on the tracks leading into manufacturing and other plants. The Master Car Builder's design, however, is such that when couplers are presented to each other at a decided angle, the knuckle tail is not forced inwardly sufficiently to permit the locking pin to drop. Hence on sharp curves, as in manufacturing plants, it is frequently necessary to make the couplings by means of a link and pins in order to enable the cars to be pulled out on to a straight track, when the link and pins are removed and the coupling made in the usual way. This not only wastes time but is also dangerous to the trainman making the link and pin coupling.

The present invention involves a standard automatic coupler of the Master Car Builder's design having all

of the advantages above specified and in which the locking pin is of simple, solid and strong construction, and has a simple vertical movement by means of which the several results are accomplished. No extra parts are provided to complicate and weaken the coupler.

In the accompanying drawings Figure 1 is a plan view of my improved coupler; Fig. 2 is a horizontal section of the same; Fig. 3 is a horizontal section showing two couplers as they lock on sharp curves; Fig. 4 is a vertical longitudinal section on the line 4—4, Fig. 2; Fig. 5 is a transverse section on the line 5—5, Fig. 2, showing the knuckle fully locked; Fig. 6 is a similar view showing the preliminary locking; Fig. 7 is a perspective view of the knuckle, showing the same upside down; Fig. 8 is a similar view of the locking pin; and Fig. 9 is a section on the line 9—9, Fig. 8.

The drawings show an automatic coupler of the Master Car Builder's type having the usual head 1 provided with a shank 2 for attaching the same to the draw bar, and two horns 3 and 4, to the former of which the knuckle 5 is pivoted by means of the pin 6. The head is recessed to provide a roof 7 and floor 8. The knuckle is provided with a tail 9 having a segmental end 10 which is shown in the form of an arm which, when the knuckle is locked, extends out through an opening 11 in the draw head and forms in effect a hook to prevent the knuckle from pulling out in case the pin 6 should break.

The roof 7 and floor 8 of the head are provided with aligning openings 12 and 13 in which works the locking pin 14. The latter is of a simple, solid construction having at its upper end the substantial rectangular locking portion 15 and at its lower end the guiding portion 16. The opening in the roof is rectangular in shape and the pin is accurately guided and firmly held in the head. It is adapted to be raised by any suitable mechanism, such as the chain 17.

Below the locking portion 15 the pin is cut away so as to form a recess 18 which permits the tail of the knuckle to freely pass the pin when the latter is raised sufficiently for the locking portion 15 to clear the knuckle tail. This recess also provides a shoulder 20 which rides on the knuckle tail and holds the pin elevated when the knuckle is open.

Below the recess 18 is a projecting portion 21, preferably an inclined shoulder as shown, which, when the pin is pulled to the full extent upwardly, engages an inclined face 22 on the bottom of the segmental knuckle tail, the effect of this contact being to throw the knuckle to open position.

The lower part of the locking portion 15 of the pin is cut away to provide a preliminary locking face 23. The knuckle tail is provided with two locking faces 24 and 25, the latter projecting beyond the former. When the locking pin is fully down its portion 15 engages the face 24 on the knuckle tail and the face 23

on the pin engages the face 25 on the tail, as shown in Fig. 5. In case the couplers are presented to each other on an angle as shown in Fig. 3, and as occurs on sharp curves the contact will not swing the 5 knuckles inwardly far enough to permit the locking pin to drop fully. But in that case the knuckles swing in far enough to permit the pin to drop part of the way, to the position shown in Fig. 6, in which the face 24 of the tail is engaged by the face 23 on the 10 pin, and the knuckle preliminarily locked. Consequently, the cars can be pulled on to a straight track, when the stretching and slackening of the train will automatically cause the knuckle to swing fully inwardly and the pin to drop to full locking position. 15 This preliminary locking is made possible by cutting away the pin to provide the face 23. It dispenses with the necessity of making link and pin couplings on sharp curves and makes the coupler automatic under all conditions.

20 The hole in the floor of the head is slightly elongated forwardly as shown at 27 so as to permit the lower end of the pin to swing forwardly when raised. The lifting means is attached in front of the center of gravity of the pin, namely, at 29, and on the front edge of the 25 pin is a shoulder 30, so that when the pin is lifted sufficiently to free the locking portion from the knuckle tail, the lower end of the pin swings forwardly by gravity and causes the shoulder 30 to swing above the floor of the head. Consequently, if the cars do not immediately pull apart, and the locking lever is released the shoulder 30 comes to rest on the floor and holds the pin in unlocked position so that when the cars do pull apart the knuckle is free to swing open. A slight projection 31 on the bottom of the knuckle 30 tail lies in the path of the shoulder 21 of the pin when the knuckle is thrown fully open and prevents the pin from being pulled entirely out of the head.

The operation of the coupler described is as follows: When the knuckle is locked the pin is in its lowermost position with the locking portion 15 lying in front of and in contact with the face 24 of the knuckle tail and the face 23 in contact with the face 25 of the knuckle tail. To unlock the coupler the pin is raised until the shoulder 30 is above the top of the knuckle tail. On account of the eccentric connection of the lifting means to the pin the lower end thereof will swing forwardly to bring the shoulder 30 above the floor of the head so that if the locking lever is then released the pin automatically sets itself in unlocked position. When the knuckle swings open the tail thereof contacts with the face 18 of the pin (which face is slightly cam shaped and has been brought in front of its normal position by the forward swinging of the lower end of the pin) and crowds the pin backwardly to disengage the shoulder 30 from the floor of the head, and the pin thus dislodged drops until the shoulder 30 rides upon the segmental end of the knuckle tail. In case the brakeman wants to re-lock the knuckle without first pulling the cars apart, it is only necessary to slightly move or shake the pin, when it readily becomes dislodged and falls back to locking position. The segmental arm 10 is of sufficient length so that the pin rides on the same in all positions of the knuckle except when in its locked position. Consequently, when the knuckle is swung to locked position

the pin automatically drops in front of the same to locking position. In case the couplers are presented to each other at a large angle, as shown in Fig. 3 and as occurs on sharp curves, the bumping of the couplers together will not swing the knuckle tail inwardly far enough to permit the pin to drop to full locking position. In that case, however, the cut-away portion forming the face 23 permits the pin to drop part way, bringing the face 23 of the pin in front of the face 24 of the knuckle tail and thus getting a preliminary locking sufficient to enable the cars to be pulled onto a straight track; when the alternate stretching and bunching of the cars causes the knuckle tail to swing inwardly to its full extent, thus permitting the pin to drop to full locking position. When the pin is raised merely to locking position the projection 21 does not contact with the face 22 of the knuckle tail, but if the pin be raised to a greater height contact between these parts occurs, and since the face 22 is inclined as shown, the effect is to throw the knuckle open, thus avoiding the necessity of a brakeman stepping in front of the car. All of these movements are secured by the mere lifting of the pin. The latter is guided and firmly held in the roof and floor of the head and is backed for its full length by the solid metal of the head, and hence is very strong. The pin itself is of simple, solid construction, giving great strength and cheapness in manufacture, and so simplifying the coupler that derangement is practically impossible.

What I claim is:

1. In a car coupler, the combination of a recessed head, a knuckle pivoted thereto and provided with a tail projecting into the head, and a vertically movable locking member in the head, said knuckle tail and locking member being so formed as to provide a primary locking when the knuckle tail is not swung fully into the head, and a full locking when said tail is swung fully into the head, and when the locking member is fully elevated to throw the knuckle open.

2. In a car coupler, the combination of a recessed head, a knuckle pivoted thereto and provided with a tail projecting into the head, said tail having a segmental end portion provided with an inclined lower face and with side locking faces in different vertical planes, and a vertically movable locking member in said head provided with co-operating vertical locking faces in different vertical planes, and with a shoulder which, when the locking member is fully elevated, engages the inclined lower face of the knuckle tail and throws said knuckle open.

3. In a car coupler, the combination of a recessed head, a knuckle pivoted thereto and provided with a tail projecting into the head, said tail having a segmental end portion provided with an inclined lower face and with two side locking faces, one projecting in advance of the other, and a vertically movable locking pin in said head provided at its upper portion with two locking faces arranged to co-operate with the locking faces on the knuckle tail, said pin being cut away below the locking faces to form a recess to permit the knuckle tail to pass and provide an upper shoulder which rides on the knuckle tail when the latter swings open and a lower shoulder or projecting portion which engages the inclined lower face of the knuckle tail when the pin is fully elevated and serves to throw the knuckle open.

4. In a car coupler, the combination of a recessed head, a knuckle pivoted thereto and provided with a tail projecting into the head and having a side locking face and a segmental end portion provided with an inclined lower face projecting in advance of the locking face, a vertically movable locking pin guided in openings in the roof and floor of said recessed head and having a side face, the upper portion of which is arranged to engage the locking

face of the knuckle tail, said pin being cut away below the locking portion to form a recess to permit the knuckle tail to pass and provide an upper shoulder which rises on the knuckle tail when the latter swings open and 5 also provide a lower shoulder or projecting portion which engages the inclined lower face of the knuckle tail when the pin is fully elevated and serves to throw the knuckle open.

5. In a car coupler, the combination of a recessed head, 10 a knuckle pivoted thereto and provided with a tail projecting into the head and having a side locking face and a segmental end portion provided with an inclined lower face which projects beyond the side locking face, a vertically movable locking pin guided in openings in the roof and 15 floor of said head and having a side face the upper portion of which is arranged to engage the locking face of the knuckle tail, said pin being cut away below said locking portion to form a recess to permit the knuckle tail to pass, 20 the shoulder at the upper edge of said recess being arranged to ride on the knuckle tail when the latter swings open, and the shoulder at the lower edge of said recess being arranged to engage the inclined lower face of the knuckle tail when the pin is fully elevated, said pin also 25 having a shoulder adapted, when the pin is elevated, to engage a projection on the coupler head and hold said pin elevated, the forward face of the recess in the pin being shaped to have the knuckle tail contact therewith when the latter swings open, thereby dislodging the pin from the 30 projection on the floor of the coupler head.

In testimony whereof, I, the said JOHN W. BARTH, have hereunto set my hand.

JOHN W. BARTH.
